NECKTIE HOLDER

Joseph B. Federico, New Baltimore, Mich., assignor to Hickok Manufacturing Co., Inc., Rochester, N. Y., a corporation of New York

Application October 17, 1947, Serial No. 780,341

1 Claim. (Cl. 24—49)

1

This invention relates to improvements in necktie holders and more particularly to tie holders of the flexible type.

An object of the invention is to provide an improved, simple, efficient necktie holder of the general type referred to adapted to be easily applied and which will securely hold a necktie properly positioned while permitting limited longitudinal movement of the tie due to different postures assumed by the wearer.

Another object of the invention is to provide an improved tie holder of the general character referred to which will automatically adjust itself to all widths of ties.

Another object of the invention is to provide an improved tie holder of the flexible type, which for the most part will be concealed from view and does not require a passing of the ends of the necktie through the flexible tie retaining means.

A particularly important novel characteristic of the invention resides in the special flexible tie retaining means provided that is positioned out of view at the back of the tie and which can be readily connected therewith.

Other important novel features of the invention lie in the particular means for connecting the flexible tie retaining means to the front of a shirt, and in the special construction of clips employed in conjunction with the flexible tie retaining means which facilitate ready attachment of the flexible tie retaining means to opposite side marginal portions of the necktie and whereby only relatively small ornamental front portions of the clips are visible neatly engaging over opposite side edge portions of the tie.

The invention, with other objects, advantages, and novel features thereof, and the particular constructions and arrangements of parts comprising the same will be understood from the following detailed description, when considered in connection with the accompanying drawings forming part hereof and illustrating a number of embodiments of the invention.

In the drawings:

Fig. 1 is a perspective view of a shirt, a collar thereon, and a necktie holder constructed in accordance with the present invention, the same being shown attached in operative position on the front of the shirt;

Fig. 2 is a top plan view of the device showing the flexible holding member engaging the ring on the clip that is to be attached to the shirt front;

Fig. 3 is a horizontal section on the line 3—3 of Fig. 1, the tie holding means being shown in top plan;

2

Figs. 4, 5, and 6 are respectively a front elevation, an end elevation, and a rear elevation of one of the clips for engagement with the necktie;

Fig. 7 is a longitudinal section on the line 7—7 of Fig. 4;

Figs. 8 and 9 are transverse sections, taken respectively on the lines 8—8 and 9—9 of Fig. 7;

Fig. 10 is a longitudinal section of a slightly modified form of clip for engagement with the necktie;

Fig. 11 is a top plan view of a modified form of the invention, the device being shown attached to a shirt and necktie;

Fig. 12 is a top plan view of another modified form of the device;

Fig. 13 is a top plan view of a further modified form of the device;

Fig. 14 is a front elevation of a modified form of means for attaching the device to a shirt;

Fig. 15 is a vertical section on the line 15—15 of Fig. 14.

While a number of preferred embodiments of the invention are illustrated in the drawings, it will be understood that minor changes and modifications may be made in the particular constructions shown, and the invention may be embodied in still other forms as will appeal to those skilled in the art and falling within the scope of the appended claims without departing from the spirit of the invention.

The invention broadly comprehends a tie holder comprising a part attachable to the front of a shirt to secure the device thereto and a pair of devices attachable to opposite side marginal portions of a necktie with a flexible chain connection between each of said devices and the part that is attached to the shirt. In the particular embodiment of the invention illustrated in Figs. 1 to 10 of the drawings, the part to be attached to the front of a shirt is shown as a clip of the lever type, the same being generally designated 1 and comprising a front bar 2 and a co-operating spring pressed clamp lever 3 pivotally connected to a portion 4 extending rearwardly

from one end of the front bar 2. The clip 1 is to be engaged with the edge portion 5 of the front of a shirt 6 as shown in Fig. 3 of the drawings. Connected with the front bar 2 of the clip 1 is a short flexible chain member 7, this chain member extending through and slidably engaging a ring 8 on the front bar 2 at the free end thereof. At each end of the chain member 7 is a clip designated generally 9, the pair of clips being adapted to be detachably secured to opposite side marginal portions of a necktie 10 as illustrated in Figs. 1 and 3. When the tie holder is

55

applied in operative position as shown in the drawings, with the clip 1 attached to the shirt front and the clips 9 attached to opposite edge portions of the necktie, the necktie will be held in proper position while allowing limited longitudinal movement of the same relatively to the shirt in response to movement of the body of the wearer. With the chain member 7 slidably engaging the ring 8 on the front bar 2 of the clip 1, the chain member can float into a self-adjusting position.

Each clip member 9 comprises front and back members 11 and 12. The front member 11 has a rearwardly extending loop portion 13 at one end pivotally connected to the back member 12 at one end thereof, the loop portion 13 having laterally projecting lugs 14 engaging apertured ears 15 on the back member 12. As shown in Figs. 3 and 7, the loop portion 13 extends beyond its pivotal connection with the back member 12 so that the pivotal connection is concealed from view from the front of the clip. The loop portion 13 terminates in a reversely curved portion 16 that cooperates with a spring tongue 17 on the back member 12, the spring tongue acting to press the front member toward the back member. On the front member 11 are teeth 18 for gripping the necktie. The back member 12 is provided at its free end with a ring with which is connected the terminal link at one end of the chain member 7. The front member 11 of the clip is longer than the back member so that its free end portion overlaps the free end portion of the back member 12. This construction, as will be understood, facilitates the ready engagement of the clips over the edge portion of the necktie. The front member of each of the clips 9 is shown with an ornamental initial letter 19 on its front face.

The modified form of clip illustrated in Fig. 10 of the drawings is the same in construction as that shown in Figs. 4 to 10 except that in this instance, the free end portion of the back member designated 20 in this view overlaps the free end portion of the front member 21.

By the special arrangement of parts hereinbefore described, a tie holder is provided that is simple in construction, that will operate efficiently, and that can be readily applied in operative position. The device is automatically adjustable to accommodate ties of different widths and when in operative position the flexible tie retaining means is disposed at the back of the necktie, and all of the tie holder that is visible from the front of the necktie is the ornamented front members of the pair of tie engaging clips fitting neatly over opposite side marginal edge portions of the tie.

In Fig. 11 of the drawings is illustrated a modified form of the device in which instead of a single flexible chain member connecting the pair of tie engaging clips to the clip attached to the shirt, the necktie engaging clips are flexibly connected by separate short chain members to the clip which secures the tie holder to the shirt. In this view 22 designates generally the lever type clip for attaching the tie holder to the shirt. 23 designates the front bar of the clip which in this instance is provided at each end thereof with a ring 24. 25 designates the tie engaging clips each connected by a short chain 26 with one end of the front bar 23 of the clip 22, one terminal link of the chain engaging a ring 24 and the other terminal link of the chain connecting with a ring 27 on the back member 28 of the clip 25. 75

As will be understood, this construction will operate to maintain the tie in proper position while permitting limited longitudinal movement of the same.

As in the construction hereinbefore described and illustrated in Figs. 1 to 10, the flexible retaining means, in this instance comprising separate chain members 26, is positioned at the back of the tie.

The modified construction illustrated in Fig. 12 is the same as that hereinbefore described except that instead of employing a lever type clip to attach the tie holder to the shirt, a clip 29 of the same construction as that shown in Figs. 4 to 7 is used for this purpose, the same being provided with a ring 30 on the free end portion of its front member 31 which is slidably engaged by the flexible chain member 32. In this view, 33 designates the tie engaging clips, each connected with one end of the flexible chain.

In Fig. 13 is illustrated another modified form of clip for attaching the tie holder to the shirt. This clip designated 34 is of the frictional spring type. It has a ring 35 at the free end of its front member 36, the clip with the ring 35 being constructed from a continuous piece of wire. In this view, 37 designates the pair of tie engaging clips and 38 is the flexible chain member extending through and slidably engaging the ring 35 on the front member 36 of the clip.

In Figs. 14 and 15 is shown another form of attaching means for securing the tie holder to a shirt. This consists of a wire loop member 39 having a narrow portion 40 and an enlarged portion 41 forming a substantially keyhole shaped opening, the loop member being adapted to be detachably engaged with a button 42 on the shirt 47 as shown in Fig. 14. On the lower end of the enlarged portion 41 of this loop member is a ring 43 with which the chain member 44 slidably engages. 45 designates one of the tie engaging clip members engaged with a side edge portion of a necktie designated 46.

What I claim is:

A necktie holder including an elongated clasp attachable to the front marginal edge of a shirt to extend transversely thereof and having a front bar and a rear clamping member, the front bar of the clasp having a ring thereon extending outwardly from its front face and disposed transversely thereof, a flexible chain member of a length less than the width of the widest portion of the outer fold of the necktie, said chain member extending through and being freely slidable in the ring on the front bar of the shirt clasp, a pair of clips, each of said clips comprising elongated front and back members connected together at opposing end portions thereof, the back member of each of said clips at its outer free end portion being permanently connected to one end of the flexible chain member, said clips being attachable to opposite side marginal portions of the outer depending fold of the necktie with the chain member and a part of the back member of each of the clips disposed behind the outer fold of the necktie, the flexible chain member when the necktie holder is in use providing a flexible connection between the clips attached to either marginal side portion of the depending fold of the necktie and the clasp attached to the shirt front, and the flexible chain member being of a length to maintain the folds of the necktie in position while allowing for limited movement.

transversely of the shirt front as well as longitudinal movement of the same relative to the shirt front.

JOSEPH B. FEDERICO.
